UNITED STATES PATENT OFFICE.

FITZ WILLIAM SARGENT, OF MAHWAH, NEW JERSEY, ASSIGNOR TO AMERICAN BRAKE SHOE & FOUNDRY COMPANY, OF MAHWAH, NEW JERSEY, A CORPORATION OF NEW JERSEY.

BACK FOR BRAKE-SHOES.

1,160,454.

Specification of Letters Patent. Patented Nov. 16, 1915.

Application filed August 28, 1915. Serial No. 47,770.

To all whom it may concern:

Be it known that I, FITZ WILLIAM SARGENT, a citizen of the United States, and a resident of Mahwah, in the county of Bergen and State of New Jersey, have made and invented certain new and useful Improvements in Backs for Brake-Shoes, of which the following is a specification.

This invention relates to reinforcing backs for brake shoes and has for its object to so design the back that a wrought metal lug may be secured thereto, and in such manner that the ends of the lug will not project below the general plane of the back. It has been the customary practice, heretofore, to attach a wrought metal lug to the brake shoe back by bending the ends thereof beneath and into contact with the lower surface of the back, which causes the ends of the lug to protrude beneath the general plane of the back and within the wearing body of the shoe. As the body of the shoe becomes worn, the ends of the wrought metal lug would be severed, allowing it to pull out and the brake shoe to fall away from the brake head. In some instances, this difficulty was overcome by crimping the central portion of the back and turning the ends of the lug into this raised crimped portion. The crimping of the back, however, is liable to be attended by the permanent injury thereto.

It is therefore, the purpose of the present invention to do away with this crimping of the back, and at the same time to dispose the ends of the wrought metal lug, either in or above the general plane of the back and securely anchor it thereto, so that the reinforcing back may be entirely worn away before the ends of the lug become severed, and with these and other objects and advantages, my invention resides in the combination and arrangement of parts and in the details of construction hereinafter described and claimed, wherein it is to be understood that changes in the precise embodiment of the invention can be made within the scope of what is claimed without departing from the spirit thereof.

The preferred embodiment of my invention is disclosed in the accompanying drawings, wherein:

Figure 1 is a view in plan of a blank from which the reinforcing back, embodying the characteristic features of my invention, is

formed. Fig. 2 is a view in cross-section taken on the line 2—2 of Fig. 1, and after the blank has been curved in its length. Fig. 3 is a similar view, with the notched sides of the back upwardly turned or bent, for the reception and securement of the ends of the wrought metal lug. Fig. 4 is a fragmental view in perspective of the finished back, with the wrought metal lug attached thereto. Fig. 5 is a view in central vertical section of a brake shoe having my improved reinforcing back incorporated therein. Fig. 6 is a similar view of a somewhat slightly modified form of wrought metal lug. Fig. 7 is a fragmental view in plan of a modified form of blank; and Fig. 8 is a view in central vertical section of a brake shoe with the modified form of reinforcing back embodied therein.

Referring specifically to the several views, the blank illustrated in Fig. 1 includes the oblong body or plate 10, in which are provided longitudinally extending openings 11, these openings being adapted to receive the molten metal of the cast body of the shoe therein and increase the anchorage therefor. The plate 10 is provided with transversely extending slits 12, the same being of limited length and extending inward from the sides of the plate. These slits are arranged in pairs upon opposite sides of the plate and are disposed symmetrically about the transverse medial line thereof, and as thus arranged, define flaps 13 upon opposite sides of the plate 10. The flaps are provided with the slots or recesses 14, which extend in the direction of the length of the plate 10, and after the flaps have been upwardly or outwardly turned, as illustrated in Fig. 3, form openings for the reception of the ends of the wrought metal lug 15. The blank, by the action of suitable forming dies, or other means, is bent and curved in its length, and the flaps 13 are turned upwardly above the convex or outer face thereof. A wrought metal lug 15, which is U-shaped in cross-section, is secured to the reinforcing back by bending the ends 16 through the openings 14, the ends extending one toward the other and transversely of the reinforcing back. The wrought metal lug is, therefore, securely clamped to the reinforcing back, and is permanently anchored in such relation by the body 18 of the shoe, which is

cast about and upon the reinforcing back and lug in the customary manner, it being noted in this connection that the lug is spoken of as being of wrought metal in contra-distinction to lugs formed of cast metal and integral with the body. The cast metal of the body of the shoe flows around and above the sides of the lug 15 so as to supplement the same and present the requisite bearing area for the brake head.

The somewhat modified form of reinforcing lug 20, illustrated in Fig. 6, is similar to the foregoing, with the exception that the ends 19 thereof are turned or bent in opposite directions so that the sides of the lug are embraced between the flaps 13 of the back, and the ends thereof project oppositely through the openings 14 therein. In this form, as in the previous form, the cast body 18 of the shoe extends above the reinforcing lug and supplements the same, as well as permanently anchoring the lug in position.

The somewhat modified form of reinforcing back, illustrated in Figs. 7 and 8, resides in the forming of the flaps 23 central of the blank rather than at the side edges thereof. This construction is accomplished by providing the blank 10' with the H-shaped slots 22, and the resulting flaps 23 are bent outward and above the plane of the back. These flaps are provided with the recesses or openings 14', and into which the ends 16' of the lug 15' are bent. The centrally disposed opening, formed by the removal of the flaps, receives the molten metal of the body therein and increases the anchorage thereof.

In service, the reinforcing back of the shoe and body may be worn completely away before the securing ends of the lug will be severed, so that all danger and likelihood of the ends of the lug becoming worn and the lug pulling away from the shoe is eliminated. This securement of the lug renders unnecessary the crimping or bridging of the central portion of the back, so that there can

be no chance of the back becoming fractured or weakened by such procedures.

What I claim is:—

1. A reinforcing back for brake shoes provided at its central portion with outwardly extending flaps, a wrought metal lug, with the ends thereof interlocking with the said flaps.

2. A reinforcing back for brake shoes with outwardly extending flaps formed integral therewith, and a wrought metal lug with the ends thereof interlocking with the said flaps.

3. A reinforcing back for brake shoes provided with outwardly extending flaps having openings therein, and a lug with the ends thereof anchored within said openings.

4. A reinforcing back for brake shoes provided with outwardly extending flaps formed integral therewith, and having recesses therein extending in the direction of the length of said back, and a lug, with the ends thereof projecting into and anchored within said openings.

5. A reinforcing back uniformly curved throughout its length, a wrought metal lug, and means formed integral with said back extending outwardly therefrom and engaging the ends of said lug, the ends of said lug being disposed above the plane of said back.

6. A brake shoe comprising a reinforcing back provided at its central portion with outwardly turned flaps, said flaps provided with openings therein, a lug extending above and across said back and with the ends thereof disposed within the openings in said flaps, and a wearing body anchored to said back and said lug.

Signed at Mahwah, in the county of Bergen and State of New Jersey, this 25th day of August A. D. 1915.

FITZ WILLIAM SARGENT.
